US0D1031374S

(12) **United States Design Patent** (10) **Patent No.:** **US D1,031,374 S**
(45) **Date of Patent:** **** Jun. 18, 2024**

(54) **CONTAINER**

- (71) Applicant: **Dometic Sweden AB**, Solna (SE)
(72) Inventors: **Christian Zachrich**, Bromma (SE);
Birk Söödi, Johanneshov (SE); **Steve**
Schwennsen, Seattle, WA (US)
(73) Assignee: **Dometic Sweden AB**, Solna (SE)
(**) Term: **15 Years**
(21) Appl. No.: **29/820,716**
(22) Filed: **Dec. 23, 2021**

(30) **Foreign Application Priority Data**

- Jun. 28, 2021 (EM) 008592976-0001

(74) *Attorney, Agent, or Firm* — Dinsmore & Shohl LLP

(57) **CLAIM**

The ornamental design for a container, as shown and described.

DESCRIPTION

FIG. 1 is a first perspective view of a first embodiment of a container showing our new design;
FIG. 2 is a second perspective view thereof;
FIG. 3 is a front view thereof;
FIG. 4 is a rear view thereof;
FIG. 5 is a first side view thereof;
FIG. 6 is a second side view thereof;
FIG. 7 is a top view thereof;
FIG. 8 is a bottom view thereof;
FIG. 9 is a first perspective view of a second embodiment of a container showing our new design;
FIG. 10 is a second perspective view thereof;
FIG. 11 is a front view thereof;
FIG. 12 is a rear view thereof;
FIG. 13 is a first side view thereof;
FIG. 14 is a second side view thereof;
FIG. 15 is a top view thereof; and,
FIG. 16 is a bottom view thereof.

The broken lines in the drawings depict portions of the container that form no part of the claimed design.

1 Claim, 16 Drawing Sheets
